Perreault & Pfleger, PLLC(57) **CLAIM**

The ornamental design of a watch winder, substantially as shown and described.

DESCRIPTION

FIG. 1 is a top perspective view of a watch winder in accordance with the present invention;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a top perspective view of the watch winder with the door in an open position.

The broken lines in the drawings depict unclaimed environmental subject matter.
